UNITED STATES PATENT OFFICE.

CORNELIUS B. PLATT AND WILLIAM S. BROWN, OF CARTHAGE, MISSOURI.

CONNECTING SPRINGS FOR USE IN BED BOTTOMS AND OTHER PLACES.

Application filed November 2, 1923. Serial No. 672,303.

To all whom it may concern:

Be it known that we, CORNELIUS B. PLATT and WILLIAM S. BROWN, citizens of the United States, residing at Carthage, in the county of Jasper and State of Missouri, have invented certain new and useful Improvements in Connecting Springs for Use in Bed Bottoms and Other Places, of which the following is a specification.

10 Our invention relates to helical springs such as are used as the top connections between the spiral springs of bed bottoms, although the invention is not limited in its applications to this particular use. Two 15 of these connecting springs are usually used together, crossing each other at right angles and being interlaced so that the tops of the coils of the springs used lie in approximately a common plane. My invention has for 20 one of its objects to render more easy the assembling of such connecting springs and their replacement should this become necessary.

In the accompanying drawings—

25 Figure 1 is a perspective view of a spring embodying our invention.

Fig. 2 is a perspective view of another spring of the form such as is now commonly used as the top connection uniting the spiral springs of bed bottoms.

30 Fig. 3 is a broken perspective view showing two springs crossed and united according to our invention.

Fig. 4 is a perspective view of a small section of a bed bottom showing the application 35 of our invention thereto.

In the accompanying drawings, A indicates the spiral springs of a bed bottom. These may be of the usual form and construction or of a special design, as may be 40 desired, and are supported in any usual or preferred manner. Their upper ends are connected by the crossed helical springs, 2 and 3. The helical spring 2 is an open or loose coil and of uniform size from end to end, being identical with the helical springs now commonly employed in the bed art, for 45 uniting the upper ends of the spiral springs A.

The present practice is to screw one of 50 these springs, 2, through the coil of another similar spring at a point approximately midway between the ends of the latter, a procedure that takes considerable time and makes a rather loose connection between them, although permitting them to lie in approximately the same planes. The crossed

springs thus united then have their ends connected with the upper coils of the spiral springs A. It will be seen that this procedure necessitates the interengaging of the crossed connecting springs before they are 60 united to the spiral springs with which they are associated.

The spring 3 which we employ is of novel construction in that one or more—the number may be varied—of the intermediate coils of the helix are of smaller size than the rest of the coils as indicated at 4. We prefer that these coils of reduced size shall lie, along one line of the spring 3 considered as a whole, 70 in the same plane as do the other, larger, coils, an arrangement that causes a pocket or recess to be formed above the coils 4 and between those coils, 5, of larger size which are next immediately beyond the reduced section 75 of the spring.

In practicing our invention a spring 2 is connected at its ends with the upper coils of diagonally opposite spiral springs A, and a spring 3 similarly connected with the upper coils of another pair of diagonally opposite springs, the springs 2 and 3 being arranged to cross each other at their middle portions. The springs 2 and 3 are united 80 with the spiral springs A before they are interconnected with each other, as in practicing our invention it is not necessary that one of these springs be screwed into a coil of the other as has heretofore been the practice. The connecting springs being united 85 to the spiral springs, and crossing each other as represented in Figs. 3 and 4, the spring 2 is pressed into the recess between the coils 5 of the spring 3, causing one of the coils, 6, of the spring 2 to overlie the 90 small coils 4, and another coil, or a portion of a coil, 7, to underlie the reduced coils 4. This interengaging of the crossed connecting springs is easily effected, the resiliency 95 of the springs permitting the parts to assume the relations just described and illustrated in Fig. 3, and when these relations have been assumed the springs lie in common planes and are so united that there is 100 less looseness between them than there is when two springs like 2 are united by screwing one into a coil of the other, as is now commonly done. The connecting springs may be as easily separated as they are 105 united, thus permitting the replacement of any spring if it becomes bent, broken or otherwise injured.

While we have described our invention as applied to springs especially intended for use as the top connections for spiral springs of bed bottoms, it is apparent that they may be used in other situations where it is desired to employ a resilient connection formed of crossed helical spring members uniting diagonally opposite objects.

We herein refer to the recess formed by reducing the size of the mid coils of the spring 3 as being above such coils, and the coil 6 of the spring 2 as passing over the reduced coils 4 and the coil 7 as underlying or passing below such coils. These terms "above", "over", "underlying" and "below" are used for ease of description and are correctly employed when the parts of the spring connection are arranged as represented in Fig. 3. It will be understood, however, that the springs might be reversed in position from the showing of the drawings, in which event the recess would be below the coils 4. It should be understood, therefore, that the terms above referred to are not used in a limiting sense as to direction, but rather indicate relationship between the several parts constituting the connection considered as a whole.

What we claim is:—

- 30 1. An elastic spring connection, comprising crossed helical springs, certain of the coils of the helix of one of the springs being of reduced size, and the other spring crossing this one at the place where its smaller coils are located.
- 20 2. An elastic spring connection, comprising crossed helical springs, one spring having the middle section of its helix of reduced size, and the other springs crossing said first spring at its said middle section.
- 35 3. An elastic spring connection of crossed helical springs one of which has in its intermediate portion a recess between coils of the spring, of greater width than the dis-

tance between coils and formed by reason 45 of certain of the coils of the helix being of reduced size, and the other spring crosses the first named spring at the place where the coils are of reduced size and the spring is recessed.

50 4. An elastic spring connection, comprising spiral springs, the mid coil of one of which springs is of smaller size than the other coils, the small size coil being arranged so as to form an open recess above 55 it and between the full size coils immediately adjacent thereto, and the other spring being of uniform size throughout and seated in the aforesaid recess where it crosses the first mentioned spring, a coil of the last 60 spring passing over the small coil of the first spring and being continued below said coil, whereby the springs are interlocked.

5. In a spring bed bottom, the combination with a set of spiral springs, of elastic 65 spring connections uniting the springs, each connection comprising cross helical springs, one of which has a short section of its mid portion formed of relatively small coils, forming a recess open from above between 70 the larger coil portions of the spring, and the other spring of the connection crossing the first spring and lying in the recess formed in the latter, the coils of the second spring passing both above and below the 75 coils of reduced size in the first mentioned spring, thus interlocking the spring and permitting the exposed surface of the connection as a whole to lie in approximately a common plane.

80 6. A helical spring adapted to be used in association with a spring that crosses it, and as a spring connection, having the coils of a short intermediate section of the spring of reduced size as compared with the coils 85 on either side of said section.

CORNELIUS B. PLATT.
WILLIAM S. BROWN.
